CLAIM

The ornamental design for the manual hoe-plow tool, shown and described.

DESCRIPTION

FIG. 1 is an enlarged isometric view of a manual hoe-plow tool showing my new design, it being shown broken away for ease of illustration;

FIG. 2 is a reduced scale front elevational view thereof;

FIG. 3 is a left side view thereof;

FIG. 4 is a back view thereof;

FIG. 5 is a right side view thereof;

FIG. 6 is an enlarged bottom view thereof; and,

FIG. 7 is an enlarged top view thereof.
